UNITED STATES PATENT OFFICE.

MARTIN B. McCLEERY, OF PLEASANTVILLE, OHIO.

CLOSET-FLUSHING TANK.

Application filed February 25, 1927. Serial No. 170,839.

The object of this invention is to provide an improved flushing tank of simple and economical construction, and also of easy, quiet and largely automatic operation.

5 The invention is embodied in the example herein shown and described the features of novelty being finally claimed.

In the accompanying drawing—

Figure 1 is a top plan view with the lid 10 removed showing the operating parts of the invention. Fig. 2 is a vertical section on the line II—II Fig. 1.

In the views 5 designates the box or casing and 6 a cover. The box has an outlet to the 15 closet bowl at 5^a. 7 designates a shell of a form resembling that of a gastropod modified, it having an inlet vent at 8, said shell being pivoted to the walls of the box on trunnions 9 at the opposite faces of the shell 20 so as to be out of balance to turn to upright position when emptied of water, and also to be out of balance to tilt to discharging position when full of water and released. The shell has a full transverse discharge at 25 10, and a transverse damming plate at 11 lightly offset at its left hand edge from the wall of the shell so as to leave a vent at 12 of smaller capacity than the main discharge at 10. Formed within the rear right hand 30 corner of the shell is an impact member or small pocket 13 of nearly the depth of the shell, it being adapted to overflow at its upper end into the main cavity of the shell and also adapted to discharge into said 35 cavity when the shell is rocked to discharging position.

At 14 is a pipe for the water supply, under suitable pressure, said pipe entering the box and provided with a rotary valve 40 (not shown) in the casing at 15, it being of ordinary form but having connected with its stem a rod 16 carrying a float 17. The character 14^a designates an extension of the supply pipe 14 beyond the valve in casing 45 15, said extension being curved at its end so that its discharge is directed into the pocket in all positions thereof as indicated by full and broken lines Fig. 2. The valve at 15 is arranged to turn on the water when 50 the float 17 is down and to shut off the same when the shell has been fully supplied.

At 18 is an ordinary spring actuated latching pin extending through the wall of the box in such position that its inner end 55 engages the end of a spring 19 to prevent the shell from tilting to flushing position until

digitally withdrawn. The spring 19 is of a form of arrangement to pass up beyond the end of the latching pin 18 to shell-retaining position after the shell has been emptied and returned to upright or normal position. The valve case 15 acts as a stop to prevent the shell from tilting too far to the right or clockwise after the return of the shell to filling position.

The operation which can be readily gathered from the foregoing is as follows: Assuming that the shell is filled and ready for the flushing operation the pin 18 is drawn out to release the shell, it tilting 70 anti-clockwise to the position shown by broken lines Fig. 2. In this tilted position the greater portion of the water in the main part of the shell rapidly flows through the outlet 10 the discharge of the main portion being completed before all the dammed water is discharged thus leaving a sufficiency of the dammed water to supply the bowl after the main or flushing discharge. The dammed water also maintains the shell in 75 said tilted position for a short interval but when such dammed water is about finally discharged the jet of water from the pipe 14^a, acting in the pocket urges the shell to its normal and latched position. The water 80 from the pipe 14^a ultimately fills the pocket and shell, the rising water in the shell causing meanwhile the rise of the float until the supply from said pipe is cut off by the closing of the valve. It will be observed, 85 therefore, that after the release of the latching pin the operation of flushing, the return of the shell to normal position, the renewal of the supply and the shutting off of the supply are entirely automatic.

90 The forms of the parts can be changed without departing from the gist of the invention as claimed.

What I claim is:

1. A closet bowl flushing device including 100 a box having an outlet, a shell having a mouth leading volute to a closed cavity above the plane of said mouth when in normal horizontal position, said shell being laterally pivoted in the walls of the box so as to be out of balance when filled with water to discharge by gravity when released from normal position, and also out of balance to return to normal position when emptied of water, means for automatically supplying water to said shell when emptied, means for automatically latching said shell upon its 105 110

return to normal position, and means to release said latch at will.

2. A closet bowl flushing device including a box having an outlet, a shell having a mouth leading voluteely to a closed cavity above the plane of the mouth when in normal position, said shell being laterally pivoted in the walls of the box so as to be out of balance when filled and also out of balance 10 to turn to normal position when emptied of water, means for automatically latching the shell in normal or filled position, a damming member in said cavity, means for automatically supplying water to said inlet 15 when the shell has been emptied, an impact member in said shell on which the water supply operates and means for controlling said supply of water.

3. A closet bowl flushing device including 20 a box having an outlet, a shell having a mouth leading voluteely to a closed cavity above the plane of the mouth when in normal position, said shell being laterally pivoted in the walls of the box so as to be out of balance when filled with water and also out 25 of balance to turn to normal position when emptied of water, mean for automatically latching the shell in normal or filled position, and a damming member in said cavity adapt- 30 ed to retard the discharge of a portion of water from said shell.

4. A closet bowl flushing device including

a box having an outlet, a shell having a mouth leading voluteely to a closed cavity 35 above the plane of the mouth when in normal position, said shell being laterally pivoted in the walls of the box so as to out of balance when filled with water and also out of balance to turn to normal position when emptied of water, means for automatically 40 latching the shell in normal or filled position, means for automatically supplying water to said inlet when the shell has been emptied, means for controlling said supply 45 of water, and a pocket in said shell opening near the mouth of the shell into which the water supply primarily enters.

5. A closet bowl flushing device including 50 a box having an outlet, a shell having a mouth leading voluteely to a closed cavity 55 above the plane of the mouth when in normal position, said shell being laterally pivoted in the wall of the box so as to be out of balance when filled with water and also out of balance to turn to normal position when 60 emptied, means for automatically latching the shell in normal or filled position, means for automatically supplying water to said shell when it has been emptied, means for controlling said supply of water to said shell, and an impact member in said shell on which the water supply primarily discharges to urge the shell to normal position.

MARTIN B. McCLEERY.
